UNITED STATES PATENT OFFICE.

CHARLES SCHENCK, OF CHICAGO, ILLINOIS, ASSIGNEE TO ELEVATOR SUPPLY &
REPAIR COMPANY, OF CHICAGO, ILLINOIS, A CORPORATION OF ILLINOIS.

Safety Appliance for Elevator-Cars.

1,090,150.

Specification of Letters Patent. Patented Mar. 17, 1914.

Application filed July 14, 1911. Serial No. 638,679.

To all whom it may concern:

Be it known that I, CHARLES SCHENCK, a citizen of the United States, and a resident of Chicago, county of Cook, and State of Illinois, have invented certain new and useful Improvements in Safety Appliances for Elevator-Cars, of which the following is a full, clear, and exact description.

The invention relates to safety appliances 10 for elevator cars and seeks to provide simple and effective means for locking the elevator shaft doors, together with a series of electromagnets for releasing the door locks, said magnets being automatically controlled 15 by the movement of the car so that the lock of any door is only released when the elevator car is opposite thereto.

A further object of the invention is to provide means whereby the circuit through the operating motor for the elevator is opened by the opening movement of the door to thereby prevent the movement of the elevator car until the door is again closed.

The invention also seeks to provide an improved construction of safety door lock which may be released by hand by the elevator conductor.

With these and other objects in view, the invention consists in the features of improvement hereinafter set forth, illustrated in the preferred form in the accompanying drawings and more particularly pointed out in the appended claims.

In the drawing, Figure 1 is a diagrammatic view of the improved safety apparatus as applied to the shaft of an elevator car, together with a diagram of the controlling circuits. Fig. 2 is a detail view of the improved safety door locking mechanism with parts in section on the line 2--2 of Fig. 3, and the cover removed. Fig. 3 is a section on the line 3--3 of Fig. 2. Fig. 4 is a view similar to Fig. 2 with the parts in the position assumed when the door is open.

45 In Fig. 1 of the drawing is represented a car 1 arranged within an elevator shaft 2 in a building having several floors 3. Cables 4 connected to the car pass over sheaves 5, 6 and 7 suitably mounted at the upper end 50 of the shaft and thence downwardly to a counterbalancing weight 8 and to a hoisting drum 9 at the lower end of the shaft. The drum is driven from a reversible electric

hooked lug 27 with the arm 24 and the shoulder 25 of the locking member. A spring is preferably provided for holding 100 the locking member in its operative and inoperative positions. As shown, this spring is in the form of a leaf spring 30 which is secured at one end to one of the side walls 105 of the casing and extends transversely across the locking member 21 and the opposite end.

motor 10. Current supply wires 11 and 12 lead to the motor and to a controlling switch 55 13 on the car and the latter is connected to the motor by the conductors 14. Doors 15 open into the elevator shaft at the several floors. The parts thus far described may be of any usual or suitable construction. 60

The safety lock for each door is arranged within a casing 16 which is secured to the inner face of the door jamb 17 by screws 18 extending through the bottom wall of the casing. The casing is provided with a cover plate 19 secured thereto by screws 20. The locking member 21 is preferably arranged to swing upon a pivot bolt 22 which extends through one end of the locking member and the reduced inner end of which is threaded 65 into a boss 23 on the bottom wall of the casing 16. On one side of the pivot 22, the locking member is provided with an extended arm 24 and a shoulder 25 with a notch 26 between these parts. The locking member cooperates with a lug 27 which is fixed to the door 15 and is provided with a hooked end 28 which engages the notch or seat 26 of the locking member 21 in the closed position of the door. In this position of the 70 parts, as shown in Fig. 2, the hooked lug 27 extends through an opening or slot 29 in the outer side wall of the casing 16 and has its hooked end 28 within the seat or notch 26 of the locking member with the shoulder 25 of the latter engaging the hooked end 28. 75 80 85

It should also be noted that in this position, the locking member abuts against the inner side wall of the casing. When the door is open, the locking member 21 swings about 90 its pivot 22 until the arm 24 thereon engages the outer side wall of the casing and in this position of the parts, the hook 28 will clear the shoulder 25. The shift of the locking member between its operative and inoperative 95 positions, illustrated respectively in Figs. 2 and 4, is effected by the engagement of the hooked lug 27 with the arm 24 and the shoulder 25 of the locking member. A spring is preferably provided for holding 10 the locking member in its operative and inoperative positions. As shown, this spring is in the form of a leaf spring 30 which is secured at one end to one of the side walls of the casing and extends transversely across 10 the locking member 21 and the opposite end.

of the spring is bent to engage the other side wall of the casing. Preferably, the free end of the spring is seated within a notch 31 in a lug 32 that receives one of the 5 screws 20. Midway between the sides of the casing, the spring 30 is bent to form a laterally projecting, substantially V-shaped lug 33 which coöperates with a pin 34 projecting from the face of the locking member 21. 10 This pin shifts past the projection 33 on the spring from one side to the other as the locking member moves between its operative and inoperative positions, so that the spring serves to hold the locking member in one 15 or the other of such positions and also assists in completing the movement of the locking member.

The shift of the locking member from operative position is normally prevented by 20 a latch 35 which is connected to a lug 36 on the outer side wall of the casing by a pivot screw 37. This latch is provided with a shoulder 38. A spring 39 extending between the latch and the inner side wall of 25 the casing normally holds the latch in position with the shoulder 38 thereon engaging the end of the arm 24 on the locking member. An electro-magnet 40 is fixed in position within one end of the casing 16 and the 30 armature 41 of this magnet is mounted upon the latch 35. When the magnet is energized the latch is shifted to release the locking member 21 and permit the opening movement of the door. Preferably, also, the end 35 of the latch extends through a slot 42 in the inner side wall of the casing so that the latch can be released manually by the conductor of the elevator car. As the safety locking appliance is arranged within the 40 elevator shaft, the latch cannot be released by passengers or other persons on the floor of the building outside of the elevator shaft, but can only be shifted to release the locking member by the conductor or other person 45 on the car and then only when the car is opposite the door.

Each of the shaft doors 15 is provided with a locking mechanism, as indicated in Fig. 1, and the circuits of the several magnets 40 which release the door locks are controlled by a part or member which is moved in correspondence with the movement of the car, so that each of the magnets is only energized to release the adjacent locking 50 member when the car is opposite the corresponding door. This circuit controlled means comprises a commutator of suitable form. That illustrated comprises a switch arm 43 arranged to move across a series of 55 individual contacts 44 and a long contact bar 45. The switch arm is connected to the car and is moved in correspondence with the movement thereof in any suitable manner. As shown, the switch arm is driven 60 from the shaft of one of the sheaves hav-

ing a worm 46 thereon which drives a worm wheel 46^a on a shaft 47. Beveled gears 48 and 49 connect the shaft 47 with a shaft 49^a whereon the commutator switch arm 43 is mounted. When the elevator car 10 is opposite one of the doors 15 the circuit through the corresponding magnet 40 is closed to release the locking member 21 and permit the opening of the door. This circuit may be traced from the battery 50 by conductor 51 to the contact bar 45, switch 43 to one of the contacts 44 and thence by one of the conductors 52 to the magnet 40 and thence by a conductor 53 and a common return wire 54 back to the battery 50. When the car moves away from the door, the switch contact 43 moves away from the corresponding contact 44. In this way, as the car travels in either direction, the circuits of the several magnets 40 are successively opened and closed, 75 the circuit of each magnet being closed to release the corresponding lock only when the car is opposite the corresponding shaft door. If for any reason the magnet 40 fails to shift the latch 35 the car conductor, when 80 his car is opposite the door, can lift the latch and thus release the lock.

To prevent the movement of the car when one of the doors is open, a series of normally closed switches 55, one at each floor, 95 is interposed in the circuit of the operating motor 10 and each of these switches is arranged to be opened by the opening movement of the corresponding door. Each of these switches 55 is laminated and is mounted upon but insulated from one arm 56 of a bell crank which is pivotally connected to a post on the bottom wall of the casing 16 by a screw bolt 57. A spring 58 connects the arm 56 to the end wall of the casing and normally holds the switch 55 in engagement with a pair of insulated contacts 59 arranged within the casing and which are interposed in series in the conductor 12. The other arm 60 of the bell crank is arranged to be engaged by the locking member 21, when the door is opened and the locking member shifted to inoperative position as shown in Fig. 4, to thereby shift the switch to open position. When any door 15 is thus opened 100 the circuit through the operating motor 10 is broken and the car can not be moved from its position opposite the door until the latter is closed. The conductors 12, 52 and 53 extend through the opposite end walls of the 105 casing 16 to the contacts 59 and to a pair of insulated binding posts 61 that are connected to the ends of the coil of the magnet 40.

It is obvious that the details set forth may be widely varied without departure from 115 the essentials of the invention as defined in the claims.

I claim as my invention:—

1. In safety appliances for elevators, the combination with the elevator car, shaft and 120

- shaft doors, a series of locking members for said doors, pivoted latches for holding said locking members in operative position, electro-magnets for releasing said latches, a commutator comprising a series of contacts connected to said magnets and a switch arm movable over said contacts, car hoisting mechanism and speed reducing gears connecting said car hoisting mechanism to said movable switch arm, whereby the latter is moved in correspondence with the movement of the car to successively engage said contacts and release the latches of said locks, substantially as described. 5
- 10 2. In safety appliances for elevators, the combination with the elevator car and operating motor therefor, an elevator shaft and shaft doors, a series of locking members for said doors, a series of latches for holding said locking members in operative position, electromagnets for releasing said latches, a member connected to and moved in correspondence to the movement of the car for successively opening and closing the circuits 20 of said magnets, and a series of switches mounted independently of but adjacent said locking members and interposed in the circuit of said operating motor, said switches being normally spring held in closed position and arranged to be engaged and opened by said locking members when the latter are shifted to inoperative position, substantially as described. 25
3. In safety appliances for elevators, the combination with the elevator car, shaft and shaft doors, of a series of locks for said doors, each of said locks comprising a casing, a notched locking member pivotally mounted within said casing, a hook-lug on the door, arranged to extend in said casing and engage and shift said locking member to and from operative position, a spring for yieldingly holding said locking member in its operative and inoperative positions, a pivoted spring held latch in said casing arranged to engage said locking member and hold the same in operative position, an electro-magnet in said casing for releasing said latch, and a switch interposed in the circuit 35 of said motor pivoted in said casing and normally spring held in closed position, said locking member being arranged to engage and open said switch when shifted to its inoperative position, substantially as described. 40
4. In safety appliances for elevators, the combination with the elevator shaft, shaft doors, the elevator car and hoisting mechanism therefor, of a series of swinging, double-armed locking members for said doors, hook lugs secured to and projecting from the edges of said doors and arranged to engage the separate arms of said locking members to shift the latter to and from operative position, said locking members having 45 seats for said hook lugs between said arms thereof, a spring for yieldingly holding each of said locking members both in its operative and in its inoperative position, latches for securing said locking members in their operative positions, electro-magnets for releasing said latches, a commutator comprising a series of contacts electrically connected to said magnets, a pivoted switch arm and speed reducing gearing interposed between said hoisting mechanism and said switch arm and arranged to move the latter in correspondence with the movement of the car to successively engage said contacts, substantially as described. 50
5. In a safety appliance for elevators, the combination with the elevator car, shaft and shaft door, of a movable locking member for said door, a latch for holding said locking member in operative position, an electro-magnet for tripping said latch, and means moved in correspondence with the movement of the car for automatically controlling the circuit of said magnet, said latch being manually releasable by the car conductor. 55
6. In safety appliances for elevators, the combination with the elevator shaft and shaft door, of a casing mounted within said shaft, a shifting locking member in said casing, a lug on the door coöperating with said member and arranged to shift the same to and from operative position, a latch for holding said locking member in operative position arranged to be manually released by the car conductor, and an electro-magnet for automatically tripping said latch. 60
7. In safety appliances for elevators, the combination with the elevator shaft and shaft door, of a casing mounted within said shaft, a shifting locking member in said casing, a lug on the door coöperating with said member and arranged to shift the same to and from operative position, a latch for holding said locking member in operative position; an electro-magnet for tripping said latch, and a normally closed switch mounted independently of said locking member and arranged to be opened by the shift of said locking member to inoperative position. 65
8. In safety appliances for elevators, the combination with the elevator car and operating electric motor therefor, the elevator shaft and shaft door, of a casing within said shaft, a swinging notched locking member in said casing, a projecting hook lug fixed to the door and arranged to extend within said casing to coöperate with said locking member and shift the latter to and from operative position, a spring held latch in said casing for holding said locking member in operative position, an electromagnet in said casing for tripping said latch, a spring for yieldingly holding said locking member in inoperative position, a switch arm and in- 70 75 80 85 90 95 100 105 110 115 120 125 130

sulated contacts independent of said locking member mounted within said casing, said contacts being interposed in the circuit of said electric motor, and a spring for normally holding said switch arm in closed position, said locking member when shifted to inoperative position being arranged to shift

said switch arm to its open position, substantially as described.
